UNITED STATES PATENT OFFICE

JOEL ISSER SCHWADRON, OF VIENNA, AUSTRIA

DESIGN FOR A STOCKING

Application filed February 7, 1930. Serial No. 34,449. Term of patent 3½ years.

To all whom it may concern:

Be it known that I, JOEL ISSER SCHWADRON, a citizen of the Austrian Republic, residing at Vienna, Austria, have invented a new, original, and ornamental Design for Stockings, of which the following is a specification, reference being had to the accompanying drawing, forming part thereof.

The figure is a side view of a stocking showing my new design.

I claim:—

The ornamental design for a stocking, as shown.

JOEL ISSER SCHWADRON.
